UNITED STATES PATENT OFFICE.

FRED H. DANIELS, OF WORCESTER, MASSACHUSETTS, ASSIGNOR TO RILEY STOKER CORPORATION, OF WORCESTER, MASSACHUSETTS, A CORPORATION OF MASSACHUSETTS.

APPARATUS FOR BURNING POWDERED FUEL.

Application filed May 29, 1923. Serial No. 642,329.

This invention relates to an improved apparatus for burning powdered coal or other similar fuel.

One serious objection to the use of powdered fuel is the form of refuse or ash produced thereby, which is largely of a very light and volatile nature and frequently creates a nuisance by deposit over the surrounding territory. A further difficulty has been encountered by the production of a small percentage of slag in the refuse which has a tendency to clog the apparatus and to interfere with the operation thereof.

It is the object of my invention to remedy these objections by radical changes in the construction of the furnace and associated mechanism, as I now encourage the formation of slag, which I afterwards collect and remove in solid masses from the furnace.

For producing such slag and in order to burn the powdered fuel to better advantage, I provide a furnace construction in which two or more streams of mixed fuel and air are oppositely directed to meet at a common combustion point, at which point very high temperatures are developed, substantially above the melting point of the ash and refuse.

Other features of my invention relate to means for collecting and removing the slag, to an improved arrangement of heating units for use with my improved combustion apparatus, and to other arrangements and combinations of parts which will be hereinafter described and more particularly pointed out in the appended claims.

A preferred form of the invention is shown in the drawings, in which

Fig. 1 is a sectional side elevation of my improved furnace, and

Fig. 2 is a sectional plan view with the top of the combustion chamber and the draft flues omitted.

Referring to the drawings, I have indicated a preferred assembly of units for carrying out my invention. I have shown a plurality of oppositely disposed powdered fuel burners or mixers 10 disposed at the four sides of a rectangular combustion chamber 11 forming the lower portion of a furnace 12. The outlets or nozzles 13 are directed to a common point at the center of the combustion chamber 11. Hoppers 14

are provided for feeding powdered coal or other similar fuel to the burners 10. Air trunks 15 are connected by suitable pipes to the burners 10.

The burners or mixers may be of any usual type and are indicated herein as of substantially cylindrical form with a series of baffle plates 16 which cause the streams of fuel and air to follow a sinuous path, so that the fuel is uniformly distributed in the blast of air before it issues from the outlet or nozzle 13.

The combustion chamber is preferably provided with a bottom 17 of fire brick or other similar material and has a central opening 18 to a lower compartment or chamber 19. As the fuel is burned at the center of the combustion chamber where the converging streams of fuel meet, the temperature produced is sufficiently high to melt a great part of the ash and refuse in the fuel, forming a relatively heavy slag which falls downward through the opening 18 into the lower compartment 19.

For disposing of the slag deposited in the compartment 19 I use a conveyor 20 formed with a series of pivotally connected troughs or forms 21 in which the slag may be deposited. The conveyor 20 is mounted upon suitable sprockets 22 and 23 and one of these sprockets may be rotated through a worm and gear connection from a motor M or by other suitable driving mechanism.

Swinging gates 24 may be provided at each side of the compartment 19 to prevent the infiltration of air at the points where the conveyor molds approach and leave the compartment. I may also provide a spray pipe 25 by which the troughs or molds 21 may be coated with lime or some other suitable substance to prevent the slag from adhering thereto. A second spray 26 may also be used to apply water to the slag as it leaves the compartment 19, thus hardening the slag to a solid mass S which will fall from the mold 21 as the conveyor passes around the sprocket 23.

For utilizing the heat produced by the combustion of the powdered fuel in the chamber 11, I prefer the boiler arrangement indicated in the drawings, in which four boilers of the water tube type, having upper and lower drums and vertically disposed wa-

ter tubes, are arranged in the form of a square in the upper portion of the furnace 12 above the combustion chamber 11. These 5 boilers 30 may be connected to a super-heater 31 disposed in the space between the boilers at the upper end of the furnace and just below the top thereof.

The dry or super-heated steam delivered 10 from the boilers or from the super-heater 15 may be withdrawn through a steam main 32 for any desired purposes. The combustion gases pass upward from the combustion chamber 11 and furnace 12 through flues 33 which preferably converge to a common 15 stack or chimney 34.

Having thus described the details of construction of one form of my invention, the 20 advantages of my improved apparatus will be readily apparent. The converging opposed streams of powdered fuel and air produce an extremely hot locus at the center of 25 the combustion chamber and, as previously stated, the temperatures developed at this point are sufficiently high to melt a substantial 30 part of the ash and waste and to produce a heavy slag therefrom which will drop to the bottom of the furnace and which may be conveniently collected in solid form by 35 the slag casting apparatus indicated in the drawings. The hot combustion gases pass to the furnace 12 and are directed against 40 the super-heater positioned at the upper end of the central passage between the boilers 30.

My improved slag casting apparatus provides 35 for automatic removal of the slag and for cooling of the slag while still in the conveyor. I also prevent adhesion of the slag to the bucket containers when deposited 40 therein by the provision of the lime spray devices and the slag is continuously and automatically discharged from the furnace in portions convenient for handling.

Having thus described my invention and 45 the advantages thereof, I do not wish to be limited to the details herein disclosed other-

wise than as set forth in the claims but what I do claim is:—

1. In a furnace, having a combustion chamber, in which substantial amounts of slag are produced, a mechanism to collect 50 and remove the slag at the bottom of said combustion chamber, said mechanism comprising a conveyor having a plurality of slag receptacles, means to move said conveyor across the bottom of said furnace in the path of the falling slag, and means to cool the slag by spraying the same in said receptacles as it leaves said furnace.

2. In a furnace, having a combustion chamber, in which substantial amounts of 60 slag are produced, a mechanism to collect and remove the slag at the bottom of said combustion chamber, mechanism comprising a conveyor having a plurality of slag receptacles, means to move said conveyor 65 across the bottom of said furnace in the path of the falling slag, and means comprising a spray device mounted externally of said furnace to apply powdered material to said slag receptacles as they approach the furnace to prevent adhesion of slag thereto.

3. In a furnace having a combustion chamber, in which substantial amounts of slag are produced, a mechanism to collect and remove 75 the slag at the bottom of said combustion chamber, said mechanism comprising a conveyor having a plurality of slag receptacles, means to move said conveyor across the bottom of said furnace in the path of the falling 80 slag, means to apply powdered material to said slag receptacles as they approach the furnace to prevent adhesion of slag thereto and means to cool the slag by spraying same in said receptacles as the receptacles leave 85 the furnace.

In testimony whereof I have hereunto affixed my signature.

FRED H. DANIELS.
